UNITED STATES PATENT OFFICE

95,456

DESIGN FOR A NETTED FABRIC

Nathan Rosen, Boston, Mass.

Application July 31, 1934, Serial No. 52,761

Term of patent 3½ years

To all whom it may concern:

Be it known that I, Nathan Rosen, a citizen of the United States, residing at Boston, in the county of Suffolk and State of Massachusetts, have invented a new, original, and ornamental Design for a Netted Fabric, of which the following is a specification, reference being had to the accompanying drawing forming part thereof, in which:—

The figure is a plan view of a portion of the fabric showing the design thereon.

The characteristic feature of the design re-

sides in a series of small diamond-shaped figures presenting a border configuration in the shape of a large diamond, the small figures being lined for color contrasts and arranged in a series of diverging rows, each row being formed by a series of dark, white, and pale colored diamond shaped figures.

I claim:

The ornamental design for a netted fabric as shown and described.

NATHAN ROSEN.
